C. E. HAVILAND.
HANDLE FOR DISHES.

No. 16,048.

Patented Apr. 14, 1885.

UNITED STATES PATENT OFFICE.

CHARLES EDWARD HAVILAND, OF LIMOGES, FRANCE.

DESIGN FOR A HANDLE FOR DISHES.

SPECIFICATION forming part of Design No. 16,048, dated April 14, 1885.

Application filed February 3, 1885. Term of patent 14 years.

To all whom it may concern:

Be it known that I, CHARLES EDWARD HAVILAND, a citizen of the United States, residing at Limoges, Republic of France, have 5 invented and produced a certain new and original Design for Handles for Dishes, fully described and represented in the following specification and the accompanying drawings, forming a part of the same.

10 This design is illustrated by two perspective views, one, Figure 1, representing a dish embodying the same as seen from the side, and Fig. 2 the same dish as seen from the end.

15 The essential feature of the design is the scarf-like formation of the handles.

It is to be understood that, although a covered vegetable dish is shown as practically embodying the design, the other dishes of a 20 table-course having handles vary in size and depth, some of which are provided with covers, while some are open vessels. Thus a souptureen is a covered dish of greater depth than a vegetable-dish, while a butter dish may be covered or not, and will be of small dimensions and shallow. A tea-cup will be a deep 25 dish of small size and have a handle arranged vertically with respect to its mouth rather than horizontally. These various arrangements of the handle will be readily understood, and come within the scope of this design.

The design is constituted by a scarf represented as gracefully curved so that its ends 1 30 shall rest upon or be in contact with the body of the dish or cover, and the central portion, 3, be raised a considerable distance therefrom, the contact ends of the scarf resting gracefully upon the said body and extending in any direction with respect to the principal 35 part of the handle, as may be desired, as is illustrated (see particularly the handle of the cover) by the end 1 being carried outward at one angle, and the end 2 curved inward and

extended at another angle. The scarf throughout its entire extent is bent and curved, so as 40 to form a graceful figure, at some points, as 4, exhibiting crinkles, and at the end 2 being partially curled up. Associated with this handle is a ribbon-like ornamentation, 5, that is curled in a serpentine manner upon the 50 body of the dish or cover; but this is a non-essential feature that may be omitted. The handles applied to the body of the dish are a reproduction of that applied to the cover and just described; but the handle applied to the 55 cover is given a somewhat greater twist when vertically considered than is the handle applied to the body of the dish. The twisted shape is more appropriate for the covers of dishes and for the handles of cups than the 60 straightened form, as will be apparent. As here illustrated, the handles are shown as applied to a dish the body B of which is formed generally of curved lines, and to the cover A, the shape of which is that of a flattened dome 65 with scalloped edges C; but, as before intimated, the outlines, both vertically and horizontally considered, of the dish and cover may be varied at will, and the scalloped decoration may be applied without departing from 70 the design.

What is claimed is—

1. The design for the handles of dishes, the same consisting of the scarf-like configuration, substantially as shown and described. 75

2. The design for a covered dish, consisting of a cover and body having handles of scarf-like configuration, substantially as shown and described.

In testimony whereof I have hereunto set 80 my hand in the presence of two subscribing witnesses.

CH. ED. HAVILAND.
